UNITED STATES PATENT OFFICE

HARRY A. JACKSON, OF NEWARK, NEW JERSEY.
COMBINED COAL AND GAS GRATE.

COMBINED COAL AND GAS GRATE.

1320,761.

Specification of Letters Patent. Patented Nov. 4, 1919.

Application filed June 5, 1919. Serial No. 301,951.

To all whom it may concern:

Be it known that I, HARRY A. JACKSON, a citizen of the United States, residing at Newark, in the county of Essex and the 5 State of New Jersey, have invented certain new and useful Improvements in Combined Coal and Gas Grates, of which the following is a specification.

This invention relates to a coal grate in which a fire can be kindled or started without the use of wood or charcoal, or if a wood fire is wanted it can be started without the use of kindling. It is primarily designed, however, for the use of hard coal stoves.

15 A further object of the invention is to provide a grate of this character in which the gas openings are protected from ashes, and which can be entirely withdrawn from the stove, through the stove front for the purpose of cleaning out said openings in case they become clogged, as it is practically impossible to prevent a certain amount of fine ash dust from settling in said openings during a more or less long period of use.

25 With these objects in view the invention consists in the novel features of construction hereinafter pointed out, set forth in the claims, and shown in the accompanying drawings, in which:—

30. Figure 1 is a plan view of the grate, end portions of the stove being indicated in dotted lines.

Fig. 2 is an irregular section on the line 2-2 of Fig. 1.

35 Fig. 3 is a section on the line 3—3 of Fig. 1.

1 In the drawings 1 designates the grate sections. These are arranged parallel to each other in the usual manner of stove
40 grates, and are rotatable, in order to clean, shake, or dump the coal fire. Each section comprises a longitudinal hollow core extending the full length of the grate, and projecting rearwardly through the stove
45 back. Extending laterally from these cores are fingers 3, which form the grate bars. These fingers are also hollow and communicate with the hollow cores of the grate sections. In normal position the fingers of
50 one section extend oppositely from those of the other section.

The fingers are slightly rounded on top and are V-shape in cross section, so that the tops of the fingers overhang the sides. This

spaces the fingers farther apart at the bottom than at the top and prevents clogging of the grate with ashes, and also serves to prevent ashes falling between the fingers clogging the gas burner openings. 55

These openings as indicated at 4 are arranged longitudinally along the sides of the fingers, and are pitched upwardly and outwardly, opening about one fourth of an inch below the tops of the fingers. Extending upwardly and outwardly they tend to direct the gas flame up between the fingers. The rear projecting ends of the cores carry funnel shaped gas receivers 6 which also serve as mixing chambers. A gas supply pipe 7 is arranged parallel to the back of the stove and has branch supply pipes 8 that extend into the mixing chambers 6, but which are not connected thereto. Air shields 9 work on the pipes 8, which are threaded for this purpose. By proper spacing of the shields 9 from the chambers 6 the amount of air fed thereto is regulated. A suitable valve, not shown, is placed at any convenient point in the pipe 7.

I have indicated in dotted lines the stove back 10. This is of course provided with suitable openings through which the cores 2 pass and in which they have their bearings. But in order to allow ready removal of the grate for cleaning these opening are large enough for the mixing chambers 6 to pass through. I therefore place on the cores bearing disks 11, which fit in the openings in the back 10 when the grate sections are in position for use. 90

The front piece 10^a in which the forward ends of the cores bear is made removable. The forward portions of the cores 2 are solid and extend in advance of the grate sections in the form of shafts 12, on which are cast the usual mutilated cog wheels for rotating the two grate sections, one of the shaft sections being extended and squared to receive the usual shaker, as indicated at 14. 95

At their outer ends the fingers 3 are connected and braced by V-shaped bars 5, which extend the length of the grate sections. 100

It will be noted that by removing the stove front 10^a the grate sections can be slipped longitudinally out of position, the mixing chamber 6 passing readily through the bearing openings normally filled by the disks 11. 105

The advantages of a grate constructed in the manner shown and described will be obvious.

What I claim is:

- 5 1. In a combined coal and gas grate, oppositely arranged rotatable sections, each section having a longitudinal hollow core, a series of hollow fingers extending laterally from one side of said core and communicating therewith, each finger being V-shaped, openings formed in the sides of the fingers and at a distance from their upper faces, the tops of the fingers overhanging said openings, and means for admitting a
- 10 15 fluid fuel to said core.

Copies of this patent may be obtained for five cents each, by addressing the "Commissioner of Patents, Washington, D. C."

2. In a coal and gas grate, a grate section having a longitudinally extending hollow core, means for admitting gas to said core, fingers extending from one side of the core, said fingers being hollow, the fingers being V-shaped and having gas openings in their sides, the longitudinal axis of said openings being inclined with respect to the finger sides, directing the flame upwardly and outwardly, and bars connecting the lower edges of the fingers, as and for the purpose set forth.

In testimony whereof I affix my signature.

HARRY A. JACKSON.
